UNITED STATES PATENT OFFICE.

FRANK M. KATZ, OF NEW YORK, N. Y., ASSIGNOR TO FRANK M. KATZ & CO. INC., OF NEW YORK, N. Y.

DESIGN FOR A LAMP SHADE.

Application filed November 17, 1923. Serial No. 7,804. Term of patent 3½ years.

To all whom it may concern:

Be it known that I, FRANK M. KATZ, a citizen of the United States of America, and resident of the city, county, and State of New York, have invented a certain new, original, and ornamental Design for a Lamp Shade, of which the following is a specification, reference being had to the accompanying drawing, forming part thereof.

In the drawing, the figure is a perspective view of a lamp shade embodying my design.

I claim:

The ornamental design for a lamp shade, as shown.

FRANK M. KATZ.
